UNITED STATES PATENT OFFICE

CHARLES F. TRAGESER, OF BALTIMORE, MARYLAND, ASSIGNOR TO STADIUM UNDER-WEAR COMPANY, INC., OF BALTIMORE, MARYLAND, A CORPORATION OF MARYLAND

PAJAMA PANTS

Application filed December 1, 1927. Serial No. 237,062.

This invention relates to the construction of pajama pants and the like, to provide the same with ample fullness at the closed back and crotch; and the objects and nature of the invention will be readily understood by those skilled in the art in the light of the following explanation of the accompanying drawings that show what I now believe to be the preferred mechanical expression or embodiment of my invention from among other forms and arrangements within the spirit and scope of my invention.

An object of the invention is to provide pants of the pajama type that are closed at the back from the waistline downwardly and upwardly to the fly opening at the front, thus having a closed seat and crotch, with an expandible or hanging somewhat bag-like seat portion of extreme fullness and capacity with the ends in view of producing pants of substantially non-elastic textile fabric that will be exceedingly durable, capable of being economically manufactured, and loose and comfortable particularly as a sleeping garment.

With this and other objects in view, the invention consists in certain novel features of structure and arrangement as more fully described and specified hereinafter.

Referring to the accompanying drawings, forming a part hereof:

Fig. 1 shows in back elevation pants constructed in accordance with my invention.

Fig. 2 shows the same in front elevation.

Fig. 3 is a bottom view of the crotch portion of the pants, showing portions of the legs and the leg seams.

Fig. 4 is a plan of the two leg blanks and the back and seat blank.

The garment shown, is, in major part, composed of the three blanks or patterns illustrated by Fig. 4, although each blank is not necessarily composed of a single uncut piece of textile fabric, but can be made up of several pieces united by seams or stitching to form the blank desired to produce the completed article of my invention.

In the particular example illustrated, each leg 1, of the garment, has inner longitudinal leg seam 2, 2', but no outside leg seam, and the body portion 3, of the garment is continu-

ous and closed around the body from one side of the fly 4, to the other side thereof, without side or other seams except at the front from the fly to the crotch and except for vertical seams at the back where the combined back and seat blank is secured into the garment, but I do not wish to so limit all features of my invention, as will hereinafter appear.

In the example shown, the waist band of the garment is formed by turning the top edge portion of the body part of the garment downwardly and stitching the same to form tube 6, for the draw string or belt 7, as is usual in pajama pants, although I do not wish to so limit all features of my invention.

The two similar longitudinal blanks *a* are folded and stitched to form the legs and body portion of the garment, with the addition of the seat and back blank *b*.

The blanks *a*, form the front of the body portion and with blank *b*, the back of the body portion, and the legs of the garment. One blank *a*, forms the left leg and major part of the left body portion of the garment, and the other blank *a*, the right leg and corresponding right major part of the body portion.

In forming the legs 1, each blank *a*, is transversely folded on itself on an approximately central longitudinal fold line, and the meeting longitudinal edges from *a'*, to *a''*, are stitched together to form the portion 2, of the inner leg seam.

The back longitudinal edge portion *a*³ of each blank *a*, above point *a''*, curves inwardly and upwardly from the point *a''*, and continues upwardly approximately at an inclination to the top edge of the blank.

Thus when the two blanks *a*, are brought together, their rear edge portions *a*³, will diverge upwardly from the meeting points *a''*, forming or leaving a space to be closed by blank *b*, which blank *b*, in the completed garment, constitutes the connecting web at the back and seat of the garment, between the edge portions *a*³, of blanks *a*. The blank *b*, is of peculiar formation to attain the desired bag or loose expansible seat formation and the more or less extreme fullness hanging

of the garment at the seat and crotch to render the garment exceedingly loose and comfortable, avoiding binding and pulling on the body of the wearer and tearing and undue stretching and wear on the garment, as the wearer rolls and turns and assumes various postures when sleeping.

In the example shown, the blank *b*, when flattened out, is extremely wide at its lower end and gradually decreases in width toward its upper end, while the recess formed by the upwardly diverging edge portions *a*³, of blanks *a*, when said blanks are flattened out, reduces in width downwardly.

The downwardly enlarging blank *b*, is preferably approximately bell shape at its lower portion with outwardly curving bulging longitudinal edges while the lower transverse end edge *b*¹, of said blank is preferably continuous and curved or concaved upwardly from one lower point or corner *b*², to the other.

The similar opposite side edges *b*³, of the blank *b*, extend from the upper end of the blank downwardly to the points or corners *b*², and these edges *b*³, are stitched to the edge portions *a*³, of the blanks *a*, respectively, to form the two seams 8, that meet the seams 2, of the two legs 1, at points *a*², and extend upwardly therefrom to the back top edge of the garment.

The concave transverse edge *b*¹, of seat and back blank *b*, is stitched to front edge portions *a*⁵, of both blanks *a*, to form the portions 2', of the inner seams of the two legs in continuation of the portions 2, of said leg seams and in fact connecting said inner leg seams and rendering them continuous across the closed crotch of the garment.

The front longitudinal edges *a*⁵, of the front sides of the two blanks *a*, are both stitched to the transverse end edge *b*¹, of blank *b*, by what is in effect one continuous seam 2' in direct continuation of the two leg seams 2. The front longitudinal edges *a*⁵, of blanks *a*, extend upwardly from points *a*², to points *a*⁶, which points *a*⁶, meet and are secured together at the center of edge *b*¹, of blank *b*, by the seam 2', and at the center of the crotch of the garment.

From this center where points *a*⁶, meet, the front vertical seam 9, extends upwardly to the front or fly opening, and said seam 9, secures together the front meeting longitudinal edge portions *a*⁷, of the two blanks *a*.

From Figs. 1, 2 and 3, of the drawings, it will be noted that the seat blank *b*, is of such formation with respect to the leg and body blanks *a*, and is so assembled therewith as to be continuous across the crotch of the garment with opposite tapered extensions extending downwardly at the inner sides of the legs along the inner leg seams, and that said blank *b*, forms a loosely hanging bag or seat and crotch portion that extends forwardly

and up at the front to seam portion 2', rendering the garment extremely comfortable and with a seat, crotch and body portion of unusual durability. If so desired, for ease in assembly, the baggy seat blank *b*, can be composed of two similar longitudinal sections secured together by a central seam in continuation of the front seam 9, but whether said blank is composed of one or more pieces, it is referred to herein as blank *b*.

Also, each blank *a*, can be composed of several sections stitched together, for instance, each can be composed of a front section and a back section stitched together at their outer meeting edges to form an outer leg seam.

As various modifications might be resorted to in matters of shape and form, I do not wish to limit my invention as defined by the following claims, to the approximately exact disclosure hereof.

What I claim is:

1. Pajama pants and the like, of substantially non-elastic fabric including a substantially non-elastic fabric combined back and seat blank extending downwardly centrally of the back and seat and forwardly and upwardly at the crotch, said blank having a concaved transverse end united to the front edge portions of the garment body by a seam extending across the crotch in continuation of the inner leg seams and downwardly diverging approximately convexed opposite longitudinal edges united to the longitudinal edges of the back of the garment body by permanent seams extending to said inner leg seams to form the garment with a closed back and seat and the lower portion of its body and seat of extreme fullness by reason of the excessive width of the portion of said blank in the lower part of the body.

2. Pajama pants and the like having a body portion and leg portions providing a permanently closed back, seat and crotch; and embodying combined body and leg blanks and a combined back and seat blank, said blanks being of approximately non-elastic fabric, said body and leg blanks being cut at their back portions to provide longitudinal back edges *a*³, approximately converging downwardly and at their lower ends approximately meeting the rear edges to be joined by the inner leg seams; the combined back and seat blank being of downwardly widening approximately bell shape with a transverse end edge, said back and seat blank being of excessive width to provide the longitudinal downwardly convexing approximately diverging side edges *b*³, stitched to said downwardly converging edges *a*³, of the backs of said body and leg blanks to close the back and seat of the garment and to provide the extreme fullness of the lower portion of the garment body and its seat, said transverse end edge of the said back and seat blank being stitched to the appropriate edges of the
